US0D1095412S

(12) **United States Design Patent** (10) **Patent No.:** **US D1,095,412 S**
(45) **Date of Patent:** **** Sep. 30, 2025**

(54) **WIRELESS CHARGER**

(71) Applicant: **SHENZHEN LECHONG TECHNOLOGY CO., LTD**, Shenzhen (CN)

(72) Inventor: **Kang Jin Xu**, Shenzhen (CN)

(73) Assignee: **SHENZHEN LECHONG TECHNOLOGY CO., LTD**, Shenzhen (CN)

(**) Term: **15 Years**

(21) Appl. No.: **29/892,795**

(22) Filed: **May 22, 2023**

(51) LOC (15) Cl. **13-02**

(52) U.S. Cl.

USPC **D13/108**

(57) **CLAIM**

The ornamental design for a wireless charger as shown and described.

DESCRIPTION

FIG. 1 is a top, front, right side perspective view of a wireless charger, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom, rear, left side perspective view thereof. The dashed broken lines in the drawing depict portions of the wireless charger that form no part of the claimed design.

1 Claim, 8 Drawing Sheets
